NECKTIE RACK

Abe R. Brothers, Brooklyn, N. Y.

Application March 14, 1934, Serial No. 715,423

8 Claims. (Cl. 211—87)

This invention relates to necktie racks and, more particularly, to racks wherein a large number of ties may be supported in readily accessible positions.

Racks of this general character have heretofore been extensively known, but those previously suggested have been open to numerous disadvantages which it is the purpose of the present invention to overcome. For example, tie racks, as heretofore made, have been so constructed that ties were adapted to be supported thereon in a confused state as to color, size, etc., so that when the intended user desired a tie to wear with a particular suit of clothes, in order to produce the desired color combination, it was necessary to sort over all of the ties on the rack in order to obtain one of the desired color or one best suited for the occasion.

One object of the present invention is to provide a simple and convenient means wherein the ties supported on the rack are arranged or segregated in accordance with the primary colors of the spectrum of the light, the ties being adapted to be arranged with their predominating colors or shades so segregated that a choice of the proper tie may be readily made without looking through all of the ties on the rack.

A further object of the invention is to provide a novel construction for supporting ties upon a suitable backing board or the like, so that the ties may be individually supported in such manner as not to inadvertently be disengaged from the rack, but to provide nevertheless for easy, manual removal or replacement of a tie on the rack.

A further object of the invention is to provide a rack which will support a large number of ties in an extremely compact manner, with each and every tie visible to an observer.

A still further object of the invention is to provide novel and efficient means for supporting the ties individually in a manner to preclude undue wear on the tie by the mechanical parts of the device and complete freedom of marking of the tie by the elements of the rack construction.

Features of the invention, other than those specified, will be apparent from the hereinafter detailed description and claims when read in conjunction with the accompanying drawing.

The accompanying drawing illustrates different practical embodiments of the invention, but the constructions therein shown, are to be understood as illustrative, only, and not as defining the limits of the invention.

Figure 1 is a front elevation of a necktie rack embodying the present invention.

Figure 2 is a section on the line 2—2 of Figure 1.

Figure 3 is a fragmental perspective view showing one end portion of the rack illustrated in Figure 1.

Figures 4 and 5 show modified forms of holding pins which may be employed to support neckties individually.

Figure 6 is a view similar to Figure 3, but showing a modified form of construction.

Referring first to Figures 1—5 of the drawing, the device of this invention is therein shown as comprising a backing board 1, which may be of any desired shape, of any size appropriate to the number of neckties for which it is desired to provide and may be constructed from any suitable material, plain or ornamented, and having square, molded or beveled edges as desired. While not limiting the invention in this regard, I preferably, however, make the backing board of wood and employ cedar wood, plain, because of the pleasing odor and attractive appearance of this material.

The backing board 1 is provided with appropriate means to hang the same from a suitable support and this means may conveniently partake of the form of a screw eye 2 screwed into the upper edge of the board. To hold the board away from the wall or other supporting surface, I preferably attach to the back of the board rubber headed tacks or buttons 3, locating the same at the four corners of the board, so that they may rest against a supporting surface to space the board therefrom, keeping the tie rack level and to preclude damage to such surface. They furthermore space the board from the wall to add thickness to the board and keep the ties away from the wall, and at the same time when cedar wood is used, the spacing of the board, as stated, permits the odor to more readily escape from the back of the board.

Associated with the front of the board are a plurality of supporting members arranged in cooperative relation to one another in groups of two or more. These groups may be disposed in various ways and my experience has shown the best results are obtained when the tie supporting members are arranged in vertical rows, the members of each row being spaced with respect to one another to properly cooperate in holding a tie in position and the rows being spaced a sufficient distance apart to preclude the ties mounted on one row of supports from interfering.

ing with the ties on the next adjacent row of supports. I may, moreover, use any appropriate number of rows of supports, but I find it convenient and thoroughly practical to make definite provision for ties of the six more common primary colors of the spectrum, although this number may be increased or diminished if desired. The colors which I prefer to provide for are red, blue, brown, gray, green and lavender. Ties 5 of the two latter colors are not extensively worn and consequently, in the preferred form of the construction, five rows of supports are provided which are designated, respectively, 4, 5, 6, 7 and 8. The rows 4, 5, 7 and 8 are intended to support ties predominating in red, blue, brown or gray, respectively, while the row 6 may serve to support the green and lavender ties, as, for example, providing for the upper half of the row 6 to support green ties and the lower half to support lavender ties. Experience has shown 10 that this arrangement is thoroughly satisfactory in practice, although I wish it understood that more or less and different colors or shades than those referred to may be provided for.

20 The individual supporting members, a plurality of which constitute the respective rows 4-8, may be constructed in various ways, but, fundamentally, they involve the employment of a member having a head and a shank. The head is 25 so constructed as not to damage fine fabrics when brought in contact therewith and of such size that, when the heads are spaced apart, an appropriate distance, hereinafter described, the shanks will be spaced a somewhat greater distance with the spacing of the latter sufficient 30 to permit a protective sleeve to be associated therewith, while leaving the spacing between adjacent sleeves greater than the spacing between adjacent heads.

35 Figures 1-3 show a very satisfactory arrangement. In accordance with the showing of these figures, I employ wire nails, each of which is provided with a shank 9 pointed at one end and having a head at its opposite end. The head 40 is preferably of spherical form or rounded in such manner as to present no rough edges. For conventional four-in-hand ties, the shank should be approximately $2\frac{1}{4}$ inches in length and should be sufficiently heavy to afford the desired 45 strength. It may be resilient or not as desired. The pointed end of each nail is adapted to be driven into the board 1 for a distance of about $\frac{1}{2}$ inch, prior to which there is slipped over the shank of the nail a protective sleeve for I may 50 conveniently use varnished woven cotton tubing or sleeving 11 of the character commonly known as "spaghetti". This material is a well known 55 commercial product, marketed in various colors and particularly useful in this connection as presently explained. Furthermore this material has a highly polished smooth surface which cannot harm the most delicate fabrics.

60 When utilizing the nail construction referred to, the nails are driven into the board in vertical rows, as shown, in such manner that the shanks will be in parallel relation to one another with adjacent sleeves spaced apart a distance somewhat in excess of the thickness of a conventional tie, while the heads 10 are spaced apart 65 a distance somewhat less than the thickness of the ordinary four-in-hand tie. The sleeves 11 are of a length slightly, though not materially, greater than the width of the narrowest portion 70 of the tie. The narrowest portion of a four-in-hand tie is approximately midway of its length

so that in placing ties on a rack, each tie is forced between the heads 10 of adjacent supports, which allow the tie to pass between them into the space between the adjacent sleeves 11. If the shanks are of resilient character, the heads 5 may be spaced closer together or be made larger whereas if the shanks are rigid the heads should be spaced at such distance that the tie may be passed between the heads by exerting slight pressure on the tie insufficient to damage the tie, 10 but sufficient to preclude inadvertent retrograde movement of the tie. By making the shanks of a length slightly, though not materially in excess of the narrow portion of the tie, the ties 15 cannot slide longitudinally from between the sleeves as relatively little movement in this direction will shift a wider portion of the tie into wedging engagement between the heads and the board and preclude further movement of the tie in this direction.

20 Ten supports are shown in each row and thus each row provides for the support of nine ties. Accordingly, in the structure, as shown with five rows, provision is made for supporting forty-five ties in properly retained relation to the rack. 25 When nine ties are supported on each of two adjacent rows of supports, as stated, the superimposed ties will overlap one another and build up a lateral thickness equal to the aggregate thickness of the ties and consequently the lateral adjacent rows of supports 4, 5, 6, 7 and 8 should be spaced apart distances equal to at least twice the aggregate thickness of the ties to be supported on any one row, in order to preclude interference 30 of the ties in one row with those on the next adjacent row or rows and to permit also any particular tie to be observed and individually removed.

35 Reference to nails 7 to serve the function of supporting members is illustrative and it will be 40 understood that other forms of support may be employed in this connection. Thus, by way of example, Figures 4 and 5 show modified forms of construction.

45 In Figure 4, a screw eye is substituted for the nail. The screw eye has a rounded curled end 12 forming a head equivalent to the head of the nail. The shank 13 corresponds to the shank 9 of the nail and is provided at its end with a screw 50 threaded portion 14, whereby the screw eyes may be attached by screwing them into the board instead of driving them, as in the case of nails. The shank 13 may be rigid or resilient and is provided with an envelope or sleeve 11 of protective material as in Figure 2.

55 The structure shown in Figure 4 is illustrated on a larger scale than in Figure 2, but, in practice, the parts would be of substantially the same size.

60 According to the further modified structure of Figure 5, a nail having a shank 9a of substantially the same length as the shank 9, but without a head, is driven into the board 1 and is surrounded with a close fitting protective sleeve 11 which projects beyond the outer end of the shank. The 65 head of the support is in the form of a ring 15 embracing the projecting end of the sleeve 11 and a screw 16 is screwed into the outer end of the sleeve to expand it within the ring 15 for the purpose of attaching the ring to the sleeve and 70 permitting the ring to function as a head to the supporting member. The ring 15 may be of any appropriate shape, ornamental or otherwise, and may be of any appropriate material.

75 One advantage of the structure of Figure 5

is that the shank $9a$ may be rigid and yet the head 15 will be resiliently or yieldably mounted with respect to the shank since the sleeve 11 is of resilient material.

5 As hereinbefore stated, one primary object of this invention is to segregate ties of different colors in a manner to permit them to be readily selected by the intended user, and it is for this purpose that the supports are arranged in rows or series and spaced apart and each adapted to support ties of a particular color or predominating color. In order to make this selection more convenient and to assist as well in the initial arrangement of the ties on the rack and subsequent replacement of the ties in proper positions, I provide for the appropriate marking of the respective rows or parts of rows. In other words, according to this invention, the respective parts of the device are colored appropriate to the ties to be associated therewith. This feature of the invention may of course be carried out in various ways. For example, the board 1 may be left in its natural state or may be varnished, enameled, stained in any single color throughout, and at the head of each row a thumb tack of appropriate color may be pressed into the board so as to be readily discernible.

As an alternative form, all of the supporting members may be covered with tubing or sleeves of one color and the heads of the nails, screw eyes or the like may be colored in accordance with the ties to be associated therewith. Furthermore, all the nails, screw eyes or the like may be covered with sleeves of different colors appropriate to the ties to be associated therewith, while the heads of these supporting members may be all the same color. Furthermore, both the heads and the sleeves of the several supports may be colored appropriate to the ties to be associated therewith.

40 It is also within the purview of this invention to dispense with the tubing or sleeves 11 , and color the supports throughout according to the ties to be associated therewith.

45 In enumerating the foregoing methods of marking for color, these are given by way of example and any one method of marking for color may be used or a combination thereof may be employed if desired. The underlying feature of the invention in this connection is that there is a clear distinction of color to show the user where ties of similar color are to be mounted on the rack in order to be properly segregated in a manner to permit easy selection when desired.

50 The structure shown in Figure 6 may be made in any of the ways hereinbefore described, but differs therefrom merely in that the board 1 , instead of being made in one piece and supported by a screw eye 2 , as shown in Figure 1, is cut into longitudinal sections $1a$, $2a$, etc. with a row of supports on each section and these several sections are suspended on a rod 17 , supported on suitable brackets 18 with spacers 19 interposed between the respective sections $1a$, $2a$, etc. One of the purposes of this showing is to illustrate that the backing is adapted for numerous variations in form without departing from this invention.

55 In the structure of Figure 6, as I have made it, the several sections $1a$, $2a$, etc. are colored wholly in the color appropriate to the particular row of supports carried thereby. The resulting structure is particularly pleasing in appearance and is such as to positively obviate any possibility of incorrect placement of ties on the rack.

In the foregoing detailed description, the supporting members have been shown in the form of nails with spherical heads, in the form of screws with eyelet heads, and in the form of nails with attached cylindrical heads. These showings, however, are to be understood as illustrative, for it will be apparent that the screw eye shown may be adapted to be driven instead of screwed into the backing board, while the nails shown may be threaded to screw into the board. Similarly, the heads employed on the various supporting members may differ within wide limits. They may be not only circular but polygonal. They may be tapered instead of spherical. In fact, they may be of any appropriate shape provided that they form between adjacent heads a relatively constricted opening through which the tie may be snugly slipped in order to rest upon shanks spaced a somewhat further distance apart. The present invention is therefore not limited to heads of particular shapes, or shanks, either screwed or driven, as the invention contemplates generally the use of supporting members with shanks and heads of any appropriate shape and the present invention is to be so construed.

30 The device of the present invention is relatively simple in construction and it possesses numerous advantages. It may be economically manufactured and may be constructed for a wide variety of sizes appropriate to support almost any number of ties without becoming unnecessarily bulky. It has the advantage that the ties cannot possibly become inadvertently displaced from the rack and yet they are all supported in readily 35 accessible positions for individual removal or replacement and in a manner so that every tie on the rack can be seen.

35 The foregoing detailed description sets forth the invention in certain preferred illustrative 40 practical forms, but the invention is to be understood as fully commensurate with the appended claims.

Having thus fully described the invention, what I claim as new and desire to secure by Letters 45 Patent is:

1. A necktie rack comprising a suitable backing board provided thereon with supporting members, each of which comprises a shank and a coaxial head, the heads of adjacent supporting members being spaced apart a distance less than the thickness of a tie to permit a tie to be snugly slipped therebetween and the shanks being parallel to one another and perpendicular to the backing board and spaced apart a distance greater than the spacing of the heads and greater than the thickness of the tie, whereby untied ties may be introduced between the heads of adjacent supporting members and retained free from pressure between adjacent shanks.

50 2. A necktie rack comprising a suitable backing board provided thereon with supporting members, each of which comprises a shank and a coaxial head, yieldable protective sleeves enveloping the shanks of said supporting members between the backing board and the head and of less diameter than said heads to protect the ties from contact with the shanks, the heads of adjacent supporting members being spaced apart a distance to permit a tie to be snugly slipped therebetween and the shanks being parallel to one another and perpendicular to the board, and spaced apart a distance sufficiently greater than the spacing of the head that ties, introduced between the heads 55

of adjacent supporting members, are retained free from pressure between adjacent shanks.

3. A necktie rack comprising a suitable backing board provided thereon with supporting members, each of which comprises a shank perpendicular to the board and a coaxial head, the heads of adjacent supporting members being spaced apart a distance to permit a tie to be snugly slipped therebetween and the shanks being parallel to one another and spaced apart a distance greater than the spacing of the heads and greater than the thickness of the tie, whereby ties may be introduced between the heads of adjacent supporting members and retained free from pressure between adjacent shanks, the shanks being of such length that the distance from the face of the backing board to the heads is greater than the minimum width of the tie and less than the maximum width of the tie.

20 4. A necktie rack embodying a backing board provided thereon with parallel, spaced apart, necktie supporting members, each of which comprises a shank, one end of which is driven into the board, a yieldable protective sleeve embracing the shank and projecting beyond the outer end thereof, a head ring embracing the projecting portion of the sleeve, and an expansion member extending into the outer end of the sleeve to expand the latter into gripping engagement with the head ring.

25 5. A necktie rack comprising a suitable backing board provided thereon with supporting members, each of which comprises a shank and a coaxial head, the heads of adjacent supporting members being spaced apart a distance less than the thickness of a tie to permit a tie to be snugly slipped therebetween and the shanks being parallel to one another and spaced apart a distance greater than the spacing of the heads and greater than the thickness of the tie, whereby untied ties may be introduced between the heads of adjacent supporting members and retained free from pressure between adjacent shanks.

30 6. A necktie rack comprising a suitable backing board provided thereon with supporting members, each of which comprises a shank and a coaxial head, protective sleeves enveloping the shanks of

said supporting members between the backing board and the head and of less diameter than said heads to protect the ties from contact with the shanks, the heads of adjacent supporting members being spaced apart a distance to permit a tie to be snugly slipped therebetween and the shanks being parallel to one another, and spaced apart a distance sufficiently greater than the spacing of the heads, that ties, introduced between the heads of adjacent supporting members, are retained free from pressure between adjacent shanks.

35 7. A necktie rack comprising a backing board provided thereon with a plurality of vertically disposed, laterally spaced apart rows of supporting members projecting forwardly from the front face of the board, each of said supporting members having a shank and a coaxial head, with the adjacent heads of the supporting members of each vertical row spaced apart a distance less than the thickness of a tie to permit a tie to be snugly slipped therebetween and with the corresponding shanks spaced apart a distance greater than the spacing of the heads and greater than the thickness of the tie, whereby untied ties may be introduced between the heads of vertically adjacent supporting members and retained free from pressure between the adjacent shanks thereof.

40 8. A necktie rack comprising a suitable backing board provided thereon with supporting members, each of which comprises a shank and a coaxial head, rotatable protective sleeves enveloping the shanks of said supporting members between the backing board and the head and of less diameter than said heads to protect the ties from contact with the shanks, the heads of adjacent supporting members being spaced apart a distance to permit a tie to be snugly slipped therebetween and the shanks being parallel to one another and perpendicular to the board, and spaced apart a distance sufficiently greater than the spacing of the heads, that ties, introduced between the heads of adjacent supporting members, are retained free from pressure between adjacent shanks.
